POLISHING MACHINE

Edward C. Lindsay, Newton Falls, Ohio, and Eugene L. Anderson, Coraopolis, Pa., assignors to Standard Steel Spring Company, Coraopolis, Pa., a corporation of Pennsylvania

Application July 10, 1948, Serial No. 37,988

9 Claims. (Cl. 51—141)

1

This invention relates to an abrasive belt polishing machine comprising a driving roll, a work roll and a tension roll, all mounted on a frame and having an abrasive belt passing around the rolls. While the invention is applicable to polishing a wide variety of articles, it will be described as applied to the polishing of automobile bumpers. The bumpers are conveyed to a position in front of the polishing machine by an endless conveyor and are then pressed by a workman against the work roll, the abrasive belt being driven continuously and being interposed between the work roll and the bumper. The workman moves the bumper while resting on the endless conveyor so as to polish different portions of the bumper.

In the accompanying drawings, which illustrate a preferred embodiment of my invention:

Figure 1 is a rear longitudinal elevation;

Figure 2 is a plan view;

Figure 3 is an end elevation taken from the right-hand side of Figure 1;

Figure 4 is a transverse section taken on the line IV—IV of Figure 1;

Figure 5 is a section taken on the line V—V of Figure 2;

Figure 6 is a section taken on the line VI—VI of Figure 2;

Figure 7 is an enlarged view of a portion of the device shown in Figure 6, the bearings being shown in section and a portion of the work roll being broken away; and

Figure 8 is a section on the line VIII—VIII of Figure 1.

Referring more particularly to the accompanying drawings, the workpiece 2 to be polished, for example, an automobile bumper, is brought to the polishing machine and supported in position in front of the polishing machine by an endless conveyor 3, the conveyor including vertical supports 4, rollers 5 and a fabric conveyor belt 6.

The frame of the polishing machine is made of tubular members 7, 8 and 9. The tubular members 7 and 8 are connected together at their left-hand ends as viewed in Figures 1 and 6. The left-hand ends of the tubular members 8 and 9 are connected together by an angle iron 11, and intermediate their ends these tubular members are connected by two plates 12. The right-hand ends of the tubular members 7, 8

2

and 9 are connected to a plate 13 which supports the motor 14 for driving a driving roll 15. A work roll 16 and a tension roll 17 also are supported by the frame, and an abrasive belt 18 passes around the driving roll, the work roll and the tension roll.

A plate 19, shown in Figures 1 and 2, is secured to the plate 13 and a large gear 20 is secured to the plate 19 by short posts 21. A stub shaft 22 connected to the gear 20 is rotatably mounted in a bearing 23 provided in a bracket 24 having a collar 25 fitting over a post 26, the collar being secured to the post by bolts 27. The post is slidable in a guideway 28 formed in a base 29. The post can be slid in its guideway 28 toward or away from the work supporting conveyor 3. The collar 25 can be raised and lowered on the post so as to raise and lower the frame so as to adjust the work roll to the proper height with respect to the bumper bar 2 being polished.

Means is provided for rotating the frame constituted by the tubular members 7, 8 and 9 so as to tilt the work roll 16 in order to polish the top 30 or either of the face portions 31 or 32 of the bumper. To provide for this tilting movement of the frame, the gear 20 meshes with a pinion 33 mounted on a shaft 34, the shaft having a worm wheel 35 secured to its other end, the worm wheel meshing with a worm 36 which is rotatable by means of a handle 37. Rotation of the handle 37 causes the pinion 33 to rotate the large gear 20 which is rigidly secured to the frame, thereby tilting the whole frame, including the work roll 16, to present it at the proper angle 35 with respect to the workpiece being polished.

In prior known abrasive belt polishing machines there has been a tendency for the belt to slip off the work roll when pressure is applied to the work roll by pressing the workpiece against it. This is particularly true where different portions of the workpiece have different curvatures because while a work roll can be adjusted to conform to one curvature, it is difficult to have it conform to different curvatures of the workpiece, and these differences in curvature exert different actions on the belt, which is backed by the work roll, and oftentimes cause the abrasive belt to slip off the work roll. This tendency of the abrasive belt to slip off the work roll when a workpiece having different curvatures

in its different portions is applied to the work roll, is overcome according to the present invention by mounting the work roll in the manner now to be described. The mounting for the work roll is shown more particularly in Figures 4-7. The work roll 16 is secured to a shaft 40, each end of the shaft being supported in a bearing 41. A metal sleeve 42 having a collar 43 integral therewith is secured to each end of the shaft, and a resilient packing material 44 is interposed between the sleeve and the bearing. Accordingly, the shaft is resiliently mounted in the bearings by the resilient packing material so that the axis of the shaft can tilt out of its normal position to a limited extent in any plane so as to conform the work roll to the contour of the workpiece which is pressed against the abrasive belt.

In addition to resiliently mounting the shaft 40 in the bearings 41, as shown in Figure 7, the bearings 41 are independently and resiliently supported from the frame in such manner that the work roll shaft can tilt in one plane out of its normal position so as to conform the work roll to the contour of the workpiece being polished. This independent resilient mounting of each of the bearings 41 is shown more particularly in Figures 4-6. Each of the bearings 41 is supported by a bearing support 46 connected to the bearing by a bolt 47. Each of the bearing supports 46 is slidable independently of the other bearing support in a guide 48 secured to the frame. The guide 48 has a plate 49 welded to a bracket 50 which is welded at each end to one of the plates 12 as shown in Figure 5. The plate 49 forming a portion of the guide lies below the sliding bearing support 46. Two side strips 51 and two top strips 52 form the remainder of the guide. A bracket 53 is secured to the plate 52 forming a portion of the guide, and a bracket 54 is secured to the sliding bearing support 46. A rod 55 passes through an opening in each of the brackets. A spring 56 surrounding the rod is interposed between the two brackets 53 and 54 and a spring 57 surrounding the rod is interposed between the bracket 54 and a nut 58 on the end of the rod. A nut 59 also is provided on the rod.

It will be seen that the bracket 53 is fixed to the guide and since the guide is fixed to the frame, the bracket 53 is fixed relative to the frame. The bearing support 46 and the bracket 54, however, are movable relative to the frame so that the work roll 16 can be moved toward or away from the workpiece. The springs 56 and 57 act in opposition to each other with respect to their tendency to move the work roll toward or away from the workpiece. The spring 56 urges the work roll away from the workpiece, whereas the spring 57 urges the work roll toward the workpiece. Tightening the nut 58 on the rod 55 compresses the spring 57 and increases its biasing force. Likewise, tightening the nut 59 on the rod increases the biasing force of the spring 56. The spring 56 preferably is stronger than the spring 57.

By the arrangement shown in Figure 6, in which each end of the shaft 40 is mounted in a bearing 41 which is independently and resiliently supported from the frame, the work roll shaft 40 can tilt in one plane out of its normal position so as to conform the work roll to the contour of the workpiece, thereby aiding in keeping the belt on the work roll. The tracking of the belt is further aided by the arrangement shown in Figure 7, wherein each end of the work

roll shaft is resiliently mounted in its bearing.

The means for mounting the tension roll 17 so as to aid in replacing an abrasive belt, adjusting the tension of the belt, and centering the belt on the work roll by movement of the tension roll is shown in Figure 8 and at the left-hand portions of Figures 1 and 2. The shaft 62 of the tension roll 17 is mounted in a slide 63 which is slidable in a guide 64. The slide has a tang portion 65 extending from its left-hand end. A ratchet rod 66 has one end 67 extending through an opening in the tang portion 65, this end portion being surrounded by a spring 68 retained in place by a nut 69. The other end 70 of the ratchet rod is provided with teeth cooperating with a pawl 71 connected to a bracket 72 which is secured to the guide 64. A lever 73 is pivoted at 74 to the bracket 72 and is pivoted at 75 to the ratchet rod 66. A brace 76 reinforces the bracket 72. Movement of the lever 73 from the dotted to the full line position shown in Figure 1 moves the ratchet rod 66 to the left against the tension of the spring 68 and moves the slide 63 and tension roll 17 to the left to maintain the tension of the abrasive belt. A belt may be changed by releasing the pawl 71 and moving the slide 63 to the right.

The guide 64 is hinged to the frame by a hinge pin 77 passing through openings in the guide and openings in hinge parts 78 secured to the angle iron 11 which is welded to the tubular members 8 and 9. Because of this hinged connection between the mounting for the tension roll and the frame, the tension roll 17 can be tilted out of its normal position about the hinge 77 as an axis so as to turn the face of the tension roll to align the belt on the work roll 16 as desired. The tension roll 17 is held in adjusted position by a bolt and nut 79 connecting a bracket 80 secured to the frame with a bracket 81 secured to the guide 64.

In the use of the apparatus the workman presses the bumper 2 against the abrasive belt 18 which is backed by the work roll 16, the bumper being moved lengthwise relative to the work roll while the bumper is supported on the moving conveyor 3. A series of polishing machines are provided, each having its work roll adjusted at a different angle in order to polish different transverse portions of the bumper. The work roll 16 not only is resiliently mounted as a whole, but each end of the work roll shaft 40 is mounted in a bearing 41 which is independently and resiliently supported from the frame so that the work roll shaft can tilt in one plane out of its normal position so as to conform the work roll to the contour of the workpiece, thereby aiding in keeping the belt on the work roll. This action is further increased by the provision of the resilient mounting of each end of the work roll shaft in its individual bearing.

The invention is not limited to the preferred embodiment, which has been given merely for purposes of illustration, but may be otherwise embodied or practiced within the scope of the following claims.

We claim:

1. In an abrasive belt polishing machine, a frame, a work roll having an abrasive belt passing around it and mounted on a shaft, a bearing supporting each end of the shaft, each bearing being independently and resiliently supported from the frame, whereby the work roll shaft can tilt in one plane out of its normal position so as

to conform the work roll to the contour of a workpiece pressed against the abrasive belt.

2. In an abrasive belt polishing machine, a frame, a work roll having an abrasive belt passing around it and mounted on a shaft, a bearing supporting each end of the shaft, a bearing support connected to each bearing, two bearing support guides connected to said frame, each bearing support being independently slidable in its guide, and biasing means associated with each bearing support and guide for limiting movement of each bearing support in its guide, whereby the work roll shaft can tilt in one plane out of its normal position so as to conform the work roll to the contour of a workpiece pressed against the abrasive belt.

3. In an abrasive belt polishing machine, a frame, a work roll having an abrasive belt passing around it and mounted on a shaft, a bearing supporting each end of the shaft, a bearing support connected to each bearing, two bearing support guides connected to said frame, each bearing support being independently slidable in its guide, a first spring associated with each guide and bearing support and urging the bearing support away from the abrasive belt, and a second spring associated with each guide and bearing support and urging the bearing support toward the abrasive belt to tighten it, whereby the work roll shaft can tilt in one plane out of its normal position so as to conform the work roll to the contour of a workpiece pressed against the abrasive belt.

4. In an abrasive belt polishing machine, a frame, a work roll having an abrasive belt passing around it and mounted on a shaft, a bearing supporting each end of the shaft, a bearing support connected to each bearing, two bearing support guides connected to said frame, each bearing support being independently slidable in its guide, a first bracket secured to each of said bearing supports, a second bracket secured to each of said guides, a rod passing through each pair of brackets constituted by a first and second bracket, a first spring on the rod between each pair of brackets, a second spring on each rod on the opposite side of said first bracket from said first spring, and a nut on each rod for compressing each spring of a pair of springs, whereby the work roll shaft can tilt in one plane out of its normal position so as to conform the work roll to the contour of a workpiece pressed against the abrasive belt.

5. In an abrasive belt polishing machine, a frame, a work roll having an abrasive belt passing around it and mounted on a shaft, a bearing resiliently supporting each end of the shaft, each bearing being independently and resiliently supported from the frame, whereby the work roll shaft can tilt in one plane out of its normal position so as to conform the work roll to the contour of a workpiece pressed against the abrasive belt.

6. In an abrasive belt polishing machine, a frame, a work roll having an abrasive belt passing around it and mounted on a shaft, a sleeve fitting over and secured to the shaft adjacent each end thereof, a bearing surrounding but spaced from each sleeve, and resilient packing

material between each bearing and sleeve, each bearing being independently and resiliently supported from the frame, whereby the work roll shaft can tilt in any plane out of its normal position so as to conform the work roll to the contour of a workpiece pressed against the abrasive belt.

5 7. In an abrasive belt polishing machine, a frame, a work roll having an abrasive belt passing around it and mounted on a shaft, a sleeve fitted over and secured to the shaft adjacent each end thereof, a collar fixed to each sleeve, a bearing surrounding but spaced from each sleeve, and resilient packing material between each bearing and sleeve, each bearing being independently and resiliently supported from the frame, whereby the work roll shaft can tilt in any plane out of its normal position so as to conform the work roll to the contour of a workpiece pressed against the abrasive belt.

10 8. In an abrasive belt polishing machine, a frame, a driving roll and a work roll and a tension roll supported by the frame, an abrasive belt passing around said rolls, a shaft on which the work roll is mounted, a bearing supporting each end of the shaft, each bearing being independently and resiliently supported from the frame, whereby the work roll shaft can tilt in one plane out of its normal position so as to conform the work roll to the contour of a workpiece pressed against the abrasive belt, a slide in which the tension roll is mounted, a guide receiving the slide, and means for maintaining the tension roll in adjusted position, said guide being hinged to the frame so that the angular position of the tension roll can be changed to align the belt on the work roll.

15 9. In an abrasive belt polishing machine, a frame, a driving roll and a work roll and a tension roll supported by the frame, an abrasive belt passing around said rolls, a shaft on which the work roll is mounted, a bearing resiliently supporting each end of the shaft, each bearing being independently and resiliently supported from the frame, whereby the work roll shaft can tilt in any plane out of its normal position so as to conform the work roll to the contour of a workpiece pressed against the abrasive belt, a slide in which the tension roll is mounted, a guide receiving the slide, and means for maintaining the tension roll in adjusted position, said guide being hinged to the frame so that the angular position of the tension roll can be changed to align the belt on the work roll.
